UNITED STATES PATENT OFFICE.

ALBERT R. CLARK, OF INDIANAPOLIS, INDIANA.

SANITARY CLOSET.

1,096,490.

Specification of Letters Patent.

Patented May 12, 1914.

Application filed March 25, 1913. Serial No. 756,704.

To all whom it may concern:

Be it known that I, ALBERT R. CLARK, a citizen of the United States, residing at Indianapolis, in the county of Marion and State of Indiana, have invented certain new and useful Improvements in Sanitary Closets, of which the following is a specification.

The object of this invention is to provide a less odorous and more sanitary closet for those situations which are not favored with sewer connections and a suitable supply of water for flushing purposes, and to this end my object is to immediately and permanently separate the solid and liquid ordure and to drain the liquids into a gravel filled sump.

A further object is to provide a water-proof vault extending sufficiently above the ground to exclude surface water, and to provide suitable receptacles in the vault for the feces, adapted for convenient removal for emptying, and to be closed in an airtight manner during such removal.

I accomplish the above and other objects, which will hereinafter appear, by the means illustrated in the accompanying drawings, in which—

Figure 1 is a longitudinal section of a closet embodying my invention, the section being on the line 1—1 of Fig. 2. Fig. 2 is a vertical cross section of the same on the line 2—2 of Fig. 1. Fig. 3 is a view in side elevation of the closet seat detached from its associated parts. Fig. 4 is a horizontal section on the line 4—4 of Fig. 3. Fig. 5 is a horizontal section through the inner wall, just above the urinal. Fig. 6 is a vertical section of one of the receptacles to retain the feces, showing the same with the lid on. Fig. 7 is a top view of said receptacle with the lid off. Fig. 8 is a vertical section on a larger scale of the receptacle lid and adjacent portions of the head, and Fig. 9 is a horizontal section of the eccentric device for locking the lid on its receptacle.

Like characters of reference indicate like parts throughout the several views of the drawings.

A vault of suitable size and shape is dug and is provided with concrete side walls 10 and floor 11 of water tight concrete. The four walls of the vault will extend a suit-

able distance above the ground level to keep surface water from entering the vault, and 55 the front wall will be oblique, as shown in Fig. 2, for the more convenient hoisting up said slope of the feces receptacles. A suitable house 12 is erected upon the walls of the vault, as shown, and this is provided with a 60 floor 13, resting loosely upon the top of the vault walls or upon the sills of the house, as convenience may dictate. This floor is adapted to swing upwardly about its rear edge in the direction shown in dotted lines 65 in Fig. 2, to allow for the placing and removal of the feces receptacles. Formed at the middle of the bottom of the vault is a sump 14 which is filled with gravel, and the floor of the vault is provided with channels 70 15 draining into the sump.

Supported by and upon the floor 13 are the upwardly tapering sheet metal stool-walls 14', oval in cross section, having front and rear pins 15' which enter holes in the 75 floor to anchor the stool. Assembled within the stool 14' and riveted or otherwise secured to its inner upper end is a downwardly tapering chute 16, oval in cross section, and considerably longer than the stool 14' to 80 provide a projecting end which is inserted through a suitable hole cut for the purpose in the floor 13. This projection is long enough to extend through a suitable opening formed in the top of a receptacle 17 and 85 to enter the receptacle a sufficient distance to prevent accidental removal. The rear wall of the chute 16 is vertical to prevent fouling by the passing feces, and the front part of the chute is provided with a vertical 90 partition 18 which defines a smaller conduit terminating a sufficient distance below the top of the stool to receive water in micturition. The upper end will be covered with a strainer to prevent the entrance of 95 clogging matter. A seat 19 and lid 20 are secured to the top of the stool.

The receptacles 17 are made out of sheet metal and have cylindrical sides and outwardly flanged upper and lower heads which 100 are located inwardly of the cylinder ends a distance equal to the depth of the flange. Extending from the upper to the lower head, near the middle of each receptacle, is a pipe 21, the walls of which have the numerous 105 perforations 22 for the drainage of all liq-

uids into it. The upper end of this pipe screws into a collar 23 riveted to the top head and its lower end extends through the lower head of the receptacle to permit the 5 contents of the pipe to discharge through the receptacle upon the floor of the vault. The liquid thus discharged upon the floor is drained through the gutters into the sump. Secured to the pipe 21, near the upper end 10 of the receptacle, is a funnel or hopper 24 which drains into the pipe through suitable perforations. This funnel is under the extended lower end of the conduit forming partition 18. The lower end of the partition 15 18 is bent toward the pipe to discharge with more certainty into the funnel, in the manner shown in Fig. 2. The receptacles are each provided with ventilating holes 25, closed when the receptacles are out of the 20 vault, by a suitable lid or valve (not shown).

A ventilating pipe 26 extends from near the bottom of the vault, through the roof of the house, as shown.

When it is desired to empty the receptacle, which will be only at long intervals, because of the separation and discharge of all liquid matter from it, the floor 13 is raised and the receptacle grasped by its handles 27, and then hoisted up the oblique 25 front wall of the vault. When out, the hole in its upper end is closed by a cover 28, having a hook 29 to reach under the head through the hole to be closed, and having a rocking cam-latch 30 diametrically opposite 30 the hook. This cam-latch, when in the position shown in Fig. 8, will pass through the hole, but when rotated a half-turn the cam will force the cover to engage the hook, and a flange on the cam will engage under 35 the head of the receptacle and lock the cover. 40

While I have described my invention with more or less minuteness as regards details of construction and arrangement and as being embodied in certain precise forms, I do not 45 desire to be limited thereto unduly or any more than is pointed out in the claims. On the contrary, I contemplate all proper changes in form, construction and arrangement, the omission of immaterial elements,

and the substitution of equivalents, as circumstances may suggest or necessity render expedient.

I claim:

1. The combination with a separating receptacle comprising a vessel having a top 55 and a bottom, a vertical pipe within the receptacle extending through said bottom, the walls of the pipe being perforated, and a vault within which the receptacle is located, said vault having a floor which drains 60 into a sump hole at one side of the vessel, and channels in the floor under the vessel discharging into said sump hole, of a stool supported above the receptacle and having a chute passing through a hole in the receptacle top and terminating within the receptacle.

2. The combination with a separating receptacle comprising a vessel having a top and bottom, a vertical pipe within the vessel 70 extending through said bottom, the walls of the pipe being perforated, and a funnel discharging into the pipe, of a separating stool supported above the receptacle, and comprising a chute terminating within the 75 receptacle and a smaller conduit within said chute discharging into the funnel in said receptacle.

3. The combination with a separating receptacle comprising a vessel having a top 80 and a bottom, the bottom being raised above the lower end of the vessel, a vertical pipe within the receptacle extending through said bottom, the walls of the pipe being perforated, and a vault within which the receptacle 85 is located, said vault having a floor which drains into a sump hole at one side of the vessel, and channels in the floor under the vessel discharging into said sump hole.

In witness whereof, I have hereunto set 90 my hand and seal at Indianapolis, Indiana, this 10th day of March, A. D. one thousand nine hundred and thirteen.

ALBERT R. CLARK. [L.S.]
